(57) **CLAIM**

The ornamental design for a diamond shaped plant holder, as shown and described.

DESCRIPTION

FIG. 1 is a front elevation view of a diamond shaped plant holder showing my new design, the back elevation view being a mirror image thereof;

FIG. 2 is a right side elevation view thereof, the left side elevation view being a mirror image thereof;

FIG. 3 is a bottom plan view thereof; and,

FIG. 4 is a perspective view thereof.

The broken lines depict environmental subject matter and form no part of the claimed design.
